BRAKE VALVE DEVICE

Florentin Kasantzoff, Berlin, Germany

Application April 23, 1930, Serial No. 446,731

5 Claims. (Cl. 303—59)

This invention relates to a triple valve or distributor for pneumatic brakes of the direct acting automatic type.

In such brakes two disadvantages often arise: 5 first brake cylinders of different sizes need different time intervals for filling up to a certain brake pressure, so that there is danger of the train being parted into two or more sections or being heavily compressed; secondly, in some of 10 the brake cylinders the proper maximum pressures are often exceeded, so that the brakes become jammed and later on releasing becomes difficult.

For avoiding these troubles, in the new triple 15 valve a member governing the air supply and exhaust to and from the brake cylinder is balanced between the brake cylinder pressure on one side and a special regulating pressure on the other side; said regulating pressure is produced 20 in a large chamber by an air supply and exhaust governed by a further member balanced between the pressures of a spring in one direction, and of the train pipe and the regulating chamber in the other direction, said further member containing 25 a yielding spring-like device acting on the latter air supply and exhaust valve so as to yield under the action of the maximum desired regulating pressure. In this device it is possible with the aid of large passages on the brake cylinder— 30 and suitable choked air passages to the regulating pressure chamber to produce different regulating pressures in predetermined time intervals which are long compared with the time required for train pipe pressure changes so that the brake 35 cylinder pressures reach predetermined degrees simultaneously and all brakes are simultaneously applied with the desired pressures, for which the device on each separate vehicle is adjusted. Further details and advantages of the new triple 40 valve will appear from the following description.

An embodiment of the invention is shown in the accompanying drawings which represent in Fig. 1 a longitudinal section of the new triple valve in the normal release position, and in Fig. 2 45 a longitudinal section of the valve in brake applying position.

Referring to the drawings, the triple valve consists of three main parts: an equalizing portion 1, an application chamber 2 supplied with the 50 pressure from device 1, and an application portion 3 governed by said application chamber pressure.

The pressure device 1 contains five chambers 4, 5, 6, 7, 8 separated from each other by an intermediate wall 9, a diaphragm 10, a further

intermediate wall 11 and second diaphragm 12. The first diaphragm 10 is provided with a hub 13 extending with a close fit through the intermediate wall 11 and ported at 14. A double seat valve 15 is arranged in an opening of the first 5 intermediate wall 9 adapted to alternately close and open both a passage 19a through said wall and also said port 14 in hub 13. The second diaphragm 12 is provided with a casing 16 containing a spring 17 and an abutment plate 18 10 pressed against a stop on said diaphragm by said spring and holding said spring under a certain predetermined tension according to the desired maximum pressure in the regulating chamber 2, 5 and arranged opposite to the hub 13 so as 15 to be engaged by the latter as soon as both diaphragms 10 and 12 approach each other.

The chamber 4 is connected to the auxiliary reservoir by a passage 19 offering a predetermined resistance to flowing air. The chamber 5 20 is connected to the application chamber 2 by a passage 20, and the next chamber 6 is open to the atmosphere through a passage 21, which also offers a predetermined resistance to flowing air. The chamber 7 is connected to the train pipe by 25 a passage 22, and the next chamber 8 to an additional reservoir 54 by a passage 23.

Between said passages 22 and 23 a throttled connection 23a is provided through a valve 24 secured to a diaphragm 25, which on its left face 30 is loaded by the brake cylinder pressure existing in a chamber 32 adjoining the diaphragm 25, while its other face is open to the atmosphere through a passage 26.

The said pressure device 1 therefore acts as 35 follows. As soon as the train pipe is charged up (for instance to 5 atmospheres) the valve 24 opens merely under the action of the train pipe pressure and the pressure retained in chamber 8 from a previous charge, acting on the right end 40 of the valve stem 24, while the brake cylinder chamber 32 adjoining the diaphragm 25 then is discharged, as described later. Thus the train pipe fills the chamber 8 and its additional reservoir 54 with air under its maximum pressure 45 which in all other positions remains constant, as the valve 24, when braking, remains closed under the action of the brake cylinder air pressures acting in chamber 32 on the left face of the diaphragm 25. The diaphragm 12 is thereby subjected on both sides to equal air pressures and remains in its middle position. The diaphragm 10 is subjected on both sides to atmospheric pressure, the application chamber 2, 5 then being discharged, as described later, and remains also in 55

its middle position under the action of its elasticity, and the double seat valve 15 closes the opening 19a in the wall 9, as it is loaded by the auxiliary reservoir pressure prevailing in the chamber 4 and by its spring, and the valve 24 remains open.

As soon as any pressure reduction (for instance to 4.5 atmospheres) is produced in the train pipe and therefore in the chamber 7, the diaphragm 12 goes downwards under the action of the higher pressure remaining in chamber 8, due to the throttling effect of the passage 23a and the large volume of chamber 8 with its additional reservoir 54, and takes with it, by the parts 16, 17, 18, and 15 13, the other diaphragm 10, so that the valve 15 closes the passage 14 and opens the passage in the wall 9 for admitting air under pressure into the chambers 5 and 2, as shown in Fig. 2.

Then the valve 24 closes the passage 23a, as shown in Fig. 2, under the action of the brake cylinder pressure arising in chamber 32, as described later, and acting on the diaphragm 25, so as to retain in chamber 8 and its additional reservoir 54 a constant pressure approximately corresponding to the maximum train pipe pressure. After some time, depending upon the throttling effect of the restricted passage 19, the pressure arising in the chamber 2-5 balances the diaphragms 10 and 12 so that they return in its middle position and the valve 15 again closes the passage 19a. The passage 14 also remains closed. If the pressure difference in the chambers 7 and 8 should exceed for instance 1.2 atmospheres according to the desired maximum pressure in the application chambers 2-5, the diaphragm 12 goes downwards and the spring 17 becomes compressed by the hub 13 due to its predetermined tension being overcome by the application pressure in chamber 5, but the diaphragm 10 remains in its middle position so that the chambers 5 and 2 remain closed and retain their regulating pressure, which at the maximum also amounts to 1.2 atmospheres. Otherwise if the train pipe pressure is raised up to a certain amount, the diaphragms 10 and 12 go upwards under the action of the pressures existing in chambers 5 and 7 against the pressure existing in chamber 8, so as to open passage 14 and discharge chambers 2 and 5, until equilibrium of the pressures in chambers 5, 7, and 8 is reached. Then the diaphragms 10 and 12 return to its middle position, so as to close passage 14 by the valve 15; passage 19a remains also closed.

Thus, the application chamber 2 receives a regulating pressure in precise dependence upon the train pipe pressure, and in a precisely determined extended time compared with the time required for train pipe pressure changes, both in raising and also in reducing its pressure, due to the throttling effect of the passages 19 and 21 and the non-throttling effect of passage 22.

As soon as the train pipe pressure is further reduced or raised the corresponding pressure changes take place in the chamber 2 and remain automatically constant against all accidental leakages, as the valve 15 is ever brought into action so as to recharge the chambers 2-5, when their pressure does not correspond to the pressure of the train pipe.

The brake cylinder application valve 3 contains four chambers 30, 31, 32, and 33, separated from the regulating chamber 2 and from each other by diaphragms 34, 35, 36 of different diameters and by an intermediate wall 37. The chamber 30 is open to the atmosphere through a pas-

sage 38. The next chamber 31 is connected by a passage 39 to a cock 40 having a groove 41 open to the atmosphere and a cross-bore 42 adapted to connect said passage 39 to another passage 43 opening into the chamber 32 which is connected to the brake cylinder at 44. Said cock serves for either opening the chamber 31 to the atmosphere, so that the diaphragm 35 becomes ineffective (for loaded vehicles), or for connecting the chambers 31 and 32 to each other, so that the diaphragm 36 becomes ineffective (for empty vehicles), so as to produce in chamber 32 for instance a desired maximum brake cylinder pressure of 3.6 or 2 atmospheres respectively, if the regulating pressure in chamber 2 amounts to 1.2 atmospheres.

The chamber 33 is connected to the train pipe through the passage 22 and additional passages 45, 46 and a check valve 47. Said chamber 33 is further connected to the auxiliary reservoir 20 through a valve 48 having a small port 49 in its poppet. Thereby the auxiliary reservoir is slowly charged through said port 49 from the chamber 33 and from the train pipe, but quickly delivers air through the valve 48 for charging the brake cylinder.

The diaphragms 34, 35, 36 are joined together by a hub 50 in which a passage 51 is so arranged that it leads from the atmospheric chamber 30 to a double-seat valve 52 extending through the chamber 32 and through an opening in the intermediate wall 37. Both valves 52 and 48 are held on their seats by a common spring 53.

The brake application portion 3 acts as follows. As long as atmospheric pressure is present in the application chamber 2 the diaphragms 34, 35, 36 remain in their middle position under the action of its elasticity, as shown in Fig. 1, and the hub 50 lies on the valve 52 without any pressure in such a manner, that in chamber 32, adapted to be easily connected to the atmosphere, exists atmospheric pressure. As soon as a pressure reduction is produced in the train pipe and thereby an application pressure is produced in the regulating chamber 2, the diaphragm 34, 35, 36 go upwards and by their hub 50 take along with them the double valve 52, so that air from the chamber 33 enters the chamber 32 and the brake cylinder, until equilibrium is restored. The brake cylinder pressure thus balanced depends upon the area proportions of the diaphragms 34 and 35 or 34 and 36 in accordance with the position of the cock 40. This action follows very rapidly on all changes of the application pressure produced by supplying air to or exhausting it from the chamber 32, so that the time needed for adjusting any brake cylinder pressure, in applying as well as in releasing the brakes, depends upon the time needed for adjusting the respective regulating pressures, as above described. Thereby it is possible to apply or release all the brakes of a train precisely at the same time and to any desired degree and without any unduly large braking forces being brought into action.

If at any time in the chamber 8 the pressure amounts to 5 atmospheres and in the chamber 7 to 3.8 atmospheres, and then for instance suddenly 7 atmospheres are produced in the chamber 1, the diaphragms 10 and 12 then go upwards, the valve 24 also opens so as to charge chamber 23-8 to 7 atmospheres and the application pressure in the chambers 5 and 2 and in the brake cylinder chamber 32 begins to fall to the pressure of the atmosphere so as to release 76.

the brakes. The diaphragm 12 then returns to its middle position.

If thereafter, in order to apply the brakes with the desired maximum force, a pressure of 3.8 atmospheres is again produced in the train pipe and chamber 1, then notwithstanding the pressure of seven atmospheres now existing in chamber 8 and loading the diaphragm 12 the pressure arising in the application chambers 2 and 5 does not extend the maximum desired pressure of 1.2 atmospheres, due to the yielding of the spring 17 which is so pretensioned as to balance the desired maximum pressure of 1.2 atmospheres in chamber 5 independently upon any movements 10 of the diaphragm 12. Consequently also the brake cylinder pressure in the chamber 32 being balanced against the application pressure by means of the diaphragms 34 and 36 or 35 respectively does not exceed the desired maximum 20 pressure of, e. g. 3.6 or 2 atmospheres respectively.

I claim:—

1. In a direct acting automatic fluid pressure brake, the combination with a brake pipe and brake cylinder, of a triple valve including a chamber connected to the brake cylinder, a regulating air pressure chamber, movable means oppositely influenced by the pressures in said chambers and including a valve member adapted to control the admission and exhaust of compressed air to and from said first mentioned chamber, means controlling the pressure in said regulating air pressure chamber including oppositely arranged chambers separated from each other by a flexible diaphragm, non-throttling passages 25 connecting each of said last named chambers with the brake pipe, valve means controlled by the air pressure in said first mentioned chamber to close the non-throttling passage to one of said last named chambers when the brake cylinder is being filled with compressed air, and a valve device operated by said flexible diaphragm to admit and exhaust compressed air to and from said regulating air pressure chamber when the pressure in the brake pipe is reduced and increased 30 respectively, said valve controlling a throttling air supply passage of such stream resistance that in said regulating air pressure chamber a regulating air pressure is produced in precise dependence upon the brake pipe pressure and in 35 a predetermined extended time compared with the time required for brake pressure changes applied through the said non-throttling passages.

2. In a direct acting automatic fluid pressure brake, the combination with a brake pipe and 40 brake cylinder, of the triple valve including a chamber connected to the brake cylinder, a regulating air pressure chamber, movable means oppositely influenced by the pressures in said chambers and including a valve member adapted to 45 control the admission and exhaust of compressed air to and from said first mentioned chamber, means controlling the pressure in said regulating air pressure chamber including oppositely arranged chambers separated from each other by 50 a flexible diaphragm, passages connecting each of said last named chambers with the brake pipe, valve means controlled by the air pressure in 55 said first mentioned chamber to close the passage to one of said last named chambers when the 55 brake cylinder is being filled with compressed air, a reservoir connected with said passage adapted to be closed by said valve means for 60 storing compressed air from said brake pipe for the purpose of maintaining a constant pressure 65 upon one side of said diaphragm, and a valve 70

device operated by said flexible diaphragm to admit and exhaust compressed air to and from said regulating air pressure chamber when the pressure in the brake pipe is reduced and increased respectively, said valve controlling a 5 throttling air supply passage of such stream resistance that in said regulating chamber a regulating air pressure is produced in precise dependence upon the brake pipe pressure and in a predetermined extended time compared with 10 the time required for brake pressure changes applied through the said passages.

3. In a direct acting automatic fluid pressure brake, the combination with a brake pipe and 15 brake cylinder, of a triple valve including a chamber connected to the brake cylinder, a regulating air pressure chamber, movable means oppositely influenced by the pressure in said chambers and including a valve member adapted to control the admission and exhaust of compressed air to and from said first mentioned chamber, said movable means forming a flexible partition between said chambers and comprising three axially spaced flexible diaphragms supporting a centrally arranged valve seat member 20 cooperating with said valve member, said valve seat member being provided with means to discharge compressed air from the first mentioned chamber when the same is moved away from said valve member, means controlling the pressure in said regulating air pressure chamber including oppositely arranged chambers separated from each other by a flexible diaphragm, passages connecting each of said last named chambers with the brake pipe, valve means controlled 25 by the air pressure in said first mentioned chamber to close the passage to one of said last named chambers when the brake cylinder is being filled with compressed air, and a valve device operated by said flexible diaphragm to admit and exhaust 30 compressed air to and from said regulating air pressure chamber when the pressure in the brake pipe is reduced and increased respectively, said valve controlling a throttling air supply passage of such stream resistance that in said regulating chamber a regulating air pressure is produced in precise dependence upon the brake pipe pressure and in a predetermined extended time compared with the time required for brake pressure changes applied through the said passages. 35

4. In a direct acting automatic fluid pressure brake, the combination with a brake pipe and 40 brake cylinder, of a triple valve including a chamber connected to the brake cylinder, a regulating air pressure chamber, movable means oppositely influenced by the pressures in said chambers and including a valve member adapted to control the admission and exhaust of compressed air to and from said first mentioned chamber, said movable means forming a flexible partition 45 between said chambers and comprising three axially spaced flexible diaphragms supporting a centrally arranged valve seat member cooperating with said valve member, said valve seat member being provided with means to discharge compressed air from the first mentioned chamber when said valve seat member is moved away from said valve member, means connecting the space between two of said diaphragms selectively with the atmosphere and with said first mentioned 50 chamber; means controlling the pressure in said regulating air pressure chamber including oppositely arranged chambers separated from each other by a flexible diaphragm, passages connecting each of said last named chambers with 55 the atmosphere and with said first mentioned 55 chamber; means controlling the pressure in said regulating air pressure chamber including oppositely arranged chambers separated from each other by a flexible diaphragm, passages connecting each of said last named chambers with 60 the atmosphere and with said first mentioned 60 chamber; means controlling the pressure in said regulating air pressure chamber including oppositely arranged chambers separated from each other by a flexible diaphragm, passages connecting each of said last named chambers with 65 the atmosphere and with said first mentioned 65 chamber; means controlling the pressure in said regulating air pressure chamber including oppositely arranged chambers separated from each other by a flexible diaphragm, passages connecting each of said last named chambers with 70 the atmosphere and with said first mentioned 70 chamber; means controlling the pressure in said regulating air pressure chamber including oppositely arranged chambers separated from each other by a flexible diaphragm, passages connecting each of said last named chambers with 75 the atmosphere and with said first mentioned 75 chamber.

- the brake pipe, valve means controlled by the air pressure in said first mentioned chamber to close the passage to one of said last named chambers when the brake cylinder is being filled with compressed air, and a valve device operated by said flexible diaphragm to admit and exhaust compressed air to and from said regulating air pressure chamber when the pressure in the brake pipe is reduced and increased respectively, said valve controlling a throttling air supply passage of such stream resistance that in said regulating chamber a regulating air pressure is produced in precise dependence upon the brake pipe pressure and in a predetermined extended time compared with the time required for brake pressure changes applied through the said passages.
5. In a direct acting automatic fluid pressure brake, the combination with a brake pipe and brake cylinder, of a triple valve including a chamber connected to the brake cylinder, a regulating air pressure chamber, movable means oppositely influenced by the pressures in said chambers and including a valve member adapted to control the admission and exhaust of compressed air to and from said first mentioned chamber, said movable means forming a flexible partition between said chambers and comprising three axially spaced flexible diaphragms supporting a centrally arranged valve seat member cooperating with said valve member, said valve seat mem-

ber being provided with a passage connecting in open position of the valve member said first mentioned chamber with one of the two spaces formed between said three diaphragms, means connecting said last named space with the atmosphere, and means for connecting the other space between said diaphragms selectively with the atmosphere and said first mentioned chamber; means controlling the pressure in said regulating air pressure chamber including oppositely arranged chambers separated from each other by a flexible diaphragm, passages connecting each of said last named chambers with the brake pipe, valve means controlled by the air pressure in said first mentioned chamber to close the passage to one of said last named chambers when the brake cylinder is being filled with compressed air, and a valve device operated by said flexible diaphragm to admit and exhaust compressed air to and from said regulating air pressure chamber when the pressure in the brake pipe is reduced and increased respectively, said valve controlling a throttling air supply passage of such stream resistance that in said regulating chamber a regulating air pressure is produced in precise dependence upon the brake pipe pressure and in a predetermined extended time compared with the time required for brake pressure changes applied through the said passages.
